say Inventor,
Oliver S. Ritz Weller,
Fricker & Bush,
Attorneys.

UNITED STATES PATENT OFFICE.

OLIVER C. RITZ WOLLER, OF CHICAGO, ILLINOIS.

COMBINATION ASH TRAY AND CIGARETTE SNUFFER.

Application filed March 26, 1927. Serial No. 178,519.

My invention relates to combination ash trays and cigarette snuffers, and has for its object the provision of a new and improved form and arrangement of parts of a device of this type by which a plurality of cigarettes may be snuffed so as to prevent continued burning or smoking and by which the device may be quickly and conveniently cleared of the snuffed cigarettes and ashes and substantially cleaned. It is another object of my invention to improve devices of this type in which a tubular part or parts are utilized for snuffing the cigarettes by providing means for pushing the cigarettes and ashes out of the tubes or sockets as may be desired, such means being preferably arranged so that all of the tubes or sockets can be cleaned at the same time by a single stroke or movement of the cleaning means.

It is another object of my invention to improve devices of this type in sundry details hereinafter pointed out. The preferred means by which I have accomplished my several objects are illustrated in the drawing and are hereinafter specifically described. That which I believe to be new and desire to cover by Letters Patent is set forth in the claims.

In the drawing,—

Fig. 1 is a top plan view of one preferred form of my improved device.

Fig. 2 is a vertical section taken at line 2—2 of Fig. 1; and

Fig. 3 is a view similar to Fig. 2 but showing a changed position of the parts.

Referring now to the several figures in which corresponding parts are indicated by the same reference characters, 10 indicates a tray formed of sheet metal, having an outwardly extending annular flange 11 formed integrally therewith, the flange 11 in turn being provided with a downwardly extending flange 12 formed integrally therewith. The outwardly extending flange 11 of the tray is provided with a plurality of sockets 13 there-in, such sockets, in the construction shown, being in the form of tube sections 14 secured at their upper ends in suitable openings through the flange 11. The sockets 13 are arranged in pairs about the tray, with grooves 15 pressed in the upper face of the flange between adjacent pairs of sockets.

Below the tray member 10, I have provided an auxiliary tray member 16 also formed of sheet metal, being provided with an upwardly extending flange 17 having a snug working fit within the flange 12 of the tray member 10

so as normally to be held by friction therein. The auxiliary tray member 16 is cut away at its central portion, the edge of the metal about the opening being flared upwardly in the form of an annular flange 18.

Between the tray members 10 and 16, I have provided a base 19 in the form of a sheet metal plate provided upon its upper face with a plurality of plungers 20 loosely mounted thereon in position to engage the lower ends of the tubular socket members 14 when the plate 19 is in position upon the upper end of the flange 18. The plungers 20, each in the form of a rod section, are loosely or pivotally mounted upon the plate 19 in order to facilitate the engagement of the plungers with the tubes 14 when the parts are being put together in their assembled position, this looseness of mounting also serving to give the plungers an easy sliding movement through the sockets as hereinafter described without the necessity for accurate machine work in the manufacture of the device. The connection of each of the plungers with the plate or base 19 comprises in the construction shown in effect a universal joint by which the desired easy adjustment is effected. The plungers 20 as shown are held in position by means of bolts 21 having beveled heads and passing loosely through openings in the base 19 into tight engagement with openings in the lower ends of the rod sections 20. A handle 22 of any suitable type is secured upon the bottom face of the base 19.

With the parts in the position as shown in Fig. 2, the sockets provided by the tube sections 14 are available for use for snuffing cigarettes in the well-understood manner, the sockets being of a size to receive the ordinary cigarette more or less snugly therein. When it is desired to clean the tray, the sockets can be cleared of cigarettes and ashes by an upward movement of the base 19 for carrying the plungers 20 upwardly through the tubes 14 into the position as shown in Fig. 3, the movement of the plate 19 to such position being effected by upward pressure on the plate or on the handle 22 through the opening defined by the flange 18. When the several sockets have been cleared of cigarettes and ashes by a single stroke of the base 19 upwardly, the plate and the plungers thereon settle by gravity again into the position as shown in Fig. 2 upon the removal of the pressure therefrom, whereupon the tray is again ready for use.

When it is desired to give the device a more

thorough cleaning, this can be effected readily and easily by the removal of the base 19 and the plungers from position between the two tray members.

5 While I prefer to employ a construction substantially as shown in my drawing, it will be understood that I do not limit the invention to the form shown except so far as certain of the claims may be specifically so limited, since it is evident that changes might well be made in the form and appearance of my device without departing from the spirit of my invention.

I claim,—

15 1. A device of the type described, comprising in combination a tray having a series of upwardly open sockets arranged thereabout, and means movably mounted on said tray adapted by a single stroke to clear said 20 sockets.

2. A device of the type described, comprising in combination a tray having a socket open through the tray, an auxiliary tray member underneath the socket, and a plunger 25 supported from said auxiliary tray and movable with respect thereto through said socket.

3. A device of the type described, comprising in combination a tray having a tubular socket therethrough, and a plunger mounted 30 in the lower end of said socket and movable upwardly with respect to the tray for clearing the socket.

4. A device of the type described, comprising in combination a tray having a plurality 35 of upwardly open sockets arranged thereabout, plungers mounted in the lower ends of said sockets respectively, and a base on which said plungers are mounted adapted by an upward movement to clear said sockets.

40 5. A device of the type described, comprising in combination a tray having a plurality of upwardly open sockets arranged thereabout, plungers mounted in the lower ends of said sockets respectively, and a base on 45 which said plungers are pivotally mounted adapted by an upward movement to clear said sockets.

6. A device of the type described, comprising in combination a tray having a plurality 50 of upwardly open sockets arranged thereabout, a base movably mounted below said tray, and a plurality of rod sections loosely mounted on said base and extending into the lower ends of said sockets, said rod sections 55 being adapted to move as plungers through said sockets upon upward movement of the base with respect to the tray.

7. A device of the type described, comprising in combination a tray formed of sheet 60 metal and having an outwardly extending flange thereabout, a plurality of tube sections mounted at their upper ends in openings

through said flange providing a series of sockets about the tray, a base movably mounted below said tray, and a plurality of plungers mounted on said base and extending into the lower ends of said sockets for clearing the sockets upon an upward movement of said base with respect to said tray.

8. A device of the type described, comprising in combination a tray formed of sheet metal and having a wide outwardly extending flange thereabout, a downwardly extending flange at the outer edge of said outwardly extending flange, a plurality of tube sections mounted at their upper ends in openings through said outwardly extending flange providing a series of sockets about the tray, a base movably mounted below said tray, a plurality of plungers loosely mounted on said base and extending into the lower ends of said sockets for clearing the sockets upon an upward movement of said base with respect to said tray, and an auxiliary tray member mounted in the lower end of said downwardly extending flange below said base.

9. A device of the type described, comprising in combination a tubular member, supporting means for holding said tubular member normally in upright position, a plunger, and means for supporting said plunger within said tubular member below the upper end thereof and for moving the plunger upwardly through the tubular member for clearing it.

10. A device of the type described, comprising in combination a tray having an upwardly open socket therein, and a plunger normally held by gravity in lowered position within said socket and movable upwardly therein for clearing the socket.

11. A device of the type described, comprising in combination a tray having a plurality of upwardly open sockets therein, a plate normally held by gravity in lowered position below said sockets, and a plurality of plungers mounted on said plate in position to enter the lower ends of said sockets and movable upwardly with said plate for clearing said sockets.

12. A device of the type described, comprising in combination a tray having a plurality of upwardly open sockets therein, a plate extending transversely below said sockets, a plurality of plungers mounted on said plate in position to enter the lower ends of said sockets and movable upwardly therethrough, and means below said plate for supporting it in position and having an opening through which access may be had to the plate for moving the plate and the plungers upwardly against the force of gravity for clearing the sockets.

OLIVER C. RITZ WOLLER.
